UNITED STATES PATENT OFFICE.

WILLIAM L. DODGE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed July 19, 1919. Serial No. 312,069.

To all whom it may concern:

Be it known that I, WILLIAM L. DODGE, a citizen of the United States, residing at Maplewood, in the county of Essex, State 5 of New Jersey, have invented certain new and useful Improvements in Telephone Systems, of which the following is a full, clear, concise, and exact description.

This invention relates to improvements 10 in signaling systems wherein signals are transmitted over a trunk line extending between widely separated offices.

Heretofore it has been proposed in the 15 patents to B. Gherardi, Nos. 1,251,363 and 1,251,364, granted December 25, 1917, to employ a signaling path common to a plurality of telephone trunk lines with apparatus at each end of the signaling path for individually associating therewith the trunk lines in 20 order that the signals incident to the establishing of connections over the trunk lines may be controlled over the common signaling path.

The present invention, which is in the 25 nature of an improvement over the systems disclosed in the patents referred to above, has for one of its objects the provision of a system of this character in which a greater number of telephone trunk lines may be 30 served by the common signaling path and in which the signals may be rapidly transmitted over the common signaling path, and in which the possibility of confusion in controlling the sending and receiving of said 35 signals over the common signaling path is reduced to a minimum.

Another object of the invention is to 35 prevent the operation of a recall signal when a subscriber's line circuit is opened by single 40 momentary reciprocation of the switchhook.

Other objects of this invention will be apparent from the description hereinafter given.

In the embodiment of the invention ill- 45 lustrated herein, the objects of the invention are accomplished by employing at each end of the common signaling path an intermittently operating distributor for sending and receiving thereover code signals, each tele-

phone trunk line served by the common 50 signaling path having a different set of code combinations individual thereto so that the particular telephone trunk line will be controlled by the code combination individual thereto. 55

Inasmuch as the intermittently operating distributors transmit over the common signaling path the code combinations of a plurality of telephone trunk lines, of which any number may be simultaneously in signaling condition, the present invention contemplates the provision of suitable means of delaying the transmission of the code combinations of a plurality of such lines simultaneously in signaling condition as well as 60 means for determining the order in which the code combinations of the lines are to be transmitted. As herein disclosed, the means for accomplishing these functions is individual to each line and comprises individual sets of relays whose circuits are so organized that when the relays associated with one telephone trunk line are actuated, the relays associated with all other lines are rendered 65 inoperative. These sets of relays also determine the code combinations to be transmitted by the distributors. 70 75

In order that the transmitted code combinations or signals may be translated into suitable signals for the appropriate telephone trunk lines, this invention contemplates the provision of receiving apparatus which is selectively responsive to the transmitted code combinations or signals to set into operation the signal of the particular 80 telephone trunk line, the code combination of which has been transmitted. The receiving apparatus, as herein disclosed, is a pyramid relay combination of a type well known in the signaling art, provision being 85 made to vary the character of the impulse over the selected path through the contacts of the pyramid selecting relays determined by the transmitted code combination for controlling the various signals associated with 90 the particular telephone trunk line. 95

According to another feature of this invention, there is but a single receiving con-

ductor for each telephone trunk line, over which the various signals for the particular trunk line are controlled. These signals are controlled by impulses of but short duration 5 and in order that a plurality of signals may be controlled thereover by these short impulses, provision is made for prolonging the operation of certain apparatus controlled over the single receiving conductor in order that at least some of the signals may be 10 maintained operated for a predetermined period. This feature has more particular reference to the recall signal which may be the signal resulting from the intermittent 15 operation of a signaling lamp. It also has particular reference to applying ringing current to the connected telephone line for a definite period of time in order that the signaling device may operate for a predetermined length of time. As disclosed herein, the means for carrying into effect this 20 feature of the invention comprises a pair of signal receiving relays normally connected with a single receiving conductor for controlling the recall signal, and a plurality 25 of cooperating slow-releasing relays which serve to maintain a ringing relay energized for a definite period of time.

For a more complete understanding of 30 this invention reference should be had to the following description considered in connection with the accompanying drawings, Figs. 1 and 2 of which, when placed end to end with Fig. 1 at the left of Fig. 2, constitute a circuit diagram of one embodiment 35 of this invention. The apparatus shown in Fig. 1 is located at the office X, that shown to the left of the dotted line 2-2 of Fig. 2 is located at the office Y, while the apparatus shown to the right of the dotted line 2-2 at the office Z. For convenience, where like apparatus is employed at both offices X and Y, it will be designated by the same reference characters, that at the office X 40 without, and that at the office Y with primes. 45

Referring to the drawings there is shown a cord circuit F located at the office X for making connections with a telephone trunk line L² extending from the office X to the office Y. The trunk line L² may be connected with a toll switching trunk circuit H extending from the office Y to the office Z, at which terminates a subscriber's telephone line G with which the toll switching trunk circuit H may be connected. While only one toll cord circuit, one toll trunk line, one toll switching trunk and one subscriber's telephone line are shown, it is to be understood that this is for the purpose of convenience only and that many such circuits may be and usually are provided in actual 50 systems.

To provide for the transmission of supervisory and other signals between operators and between operators and subscribers 55

in connection with the establishment of connections over the various trunk lines, a signaling path P common to a plurality of trunk lines extends from the central office X to central office Y.

The various trunk lines to which the signaling path P is common are individually associated with the signaling path by means of intermittently operating distributors similar to the so-called start-stop distributors employed in printing telegraphy. In transmitting signals from the office X over the common signaling path P, the sending or transmitting start-stop distributor TD is employed. At the office X there is associated with each toll trunk line a set of three relays such as K¹, M¹, N¹ and K², M², N², etc. When a signal originates at the outgoing end of one of the trunk lines, signal control leads A, B and C individual thereto are rendered effective to cause the operation of the relays of the associated set which thereupon perform the triple function of locking out the relays of other lines on which signals are originated at the same time, of determining the order in which the signals shall be transmitted and of translating such signals into code combinations or code signals which are transferred to a set of storing relays 1 to 5 inclusive for the purpose of storing the code combination or code signal until it has been transmitted by the transmitting or sending distributor TD. The position of the storing relays 1 to 5, which are controlled by the M relays individual to the trunk lines, control the polarities of signaling current connected with the individual sending segments of the sending distributor TD.

At the office Y the code combinations or code signals are received by means of an intermittently operating receiving start-stop distributor RD'. In order to translate the received code signals into suitable signals and to select the appropriate line, pyramid selecting relays are provided and are controlled by locking relays whose energizing circuits are controlled directly from the individual receiving segments of the receiving distributor RD'.

Referring more in detail to the apparatus provided at the office Y for receiving the code signals transmitted over the common signaling path P, the receiving distributor RD' is controlled by differential polarized relay 40' connected in the common signaling path P. When the alternate contact is first closed, the release magnet RDM' of the receiving distributor RD' is energized and releases the brush arm controlled thereby which is thereupon rotated through one complete cycle. Relay 39' which is normally energized over a circuit from battery through segment 11', the brush arm and segment 12' of the receiving distributor RD', holds open

its contact which is in the locking circuits of locking relays 41' to 45' inclusive whose energizing windings are connected with the respective individual receiving segments 1' to 5' inclusive, of the receiving distributor RD'. Relays 41' to 43' inclusive, control relays 46' to 52' inclusive, comprising the pyramid selecting relay combination which cooperates with locking relay 44' to select the signal receiving leads D' terminating in contacts of the relays 46' to 49' inclusive. Locking relay 45' controls the polarity of signaling current connected with the selected signal-receiving lead for determining the signal to be operated.

For transmitting over the common signaling path P signals originating at the office Y, a sending distributor, storing relays and sets of three relays similar to the equipment shown and described in connection with the office X are provided. Such sending equipment is indicated by the small dotted rectangle designated SE'. In order that the code signals transmitted over the common signaling path P from the office Y may be properly received at the office X, receiving equipment similar to the receiving distributor RD' the pyramid selecting relays and locking relays described in connection with the receiving of signals at the office Y is provided at the office X. This receiving equipment is indicated by the dotted rectangle designated RE.

Having in mind this brief description of the apparatus shown in the drawing it is thought that the invention will be thoroughly understood from a description of the operation of the system as shown.

Connection of cord circuit F with trunk line L².

The operator at the office X desiring to establish a connection with the telephone line G which terminates at the office Z, connection with which must be established through the office Y, communicates with the operator at office Y over an order wire circuit (not shown). The operator at the office X ascertaining from the operator at the office Y that the connection with the telephone line G is to be completed over trunk line L² inserts calling plug 20 of the cord circuit F into jack 21 of trunk L². Relay 22 thereupon operates over a circuit from battery through supervisory lamp 23, sleeve contacts of the plug 20 and the jack 21 and winding of relay 22 to ground. Relay 22 in opening its right-hand normal contact causes the release of a normally energized relay 24 and in closing its left-hand alternate contact causes the energization of two slow release relays 25 and 26. Relay 25 operates over a circuit from battery through the left-hand alternate contact of relay 22, winding of relay 25 and the normal contact of signal receiving relay 27 to ground, while relay 26 is energized over a

circuit from battery through the left-hand alternate contact of relay 22, winding of relay 26, normal contact of signal receiving relay 28 and the normal contact of slow-release relay 29 to ground. The energization of relay 26 disconnects the energizing winding of the signal receiving relay 27 from the signal receiving lead or circuit D² associated with trunk line L². The disconnection of right-hand winding of signal receiving relay 27 from the signal receiving lead D² prevents the false operation of the signal receiving relay 27 upon the transmission of the first signal from the office Y over the common signaling path P as will more fully hereinafter appear.

Assuming that no other trunk lines are in signal initiating condition at the time of the deenergization of the normally energized relay 24, the closure of contact 30 thereof causes the operation of relay N² over a circuit from battery through the right-hand alternate contact of relay 22, contact 30 of relay 24, signal control lead B², right-hand winding of relay N² and the contact of relay K¹ to ground. The circuit which has just been traced is established irrespective of the condition of relays corresponding to K², M², N² of higher numbered trunks but is not established if any of the relays of the K group of lower numbered trunks are energized. The relay N² upon being energized completes a locking circuit for itself which may be traced from battery through the left-hand winding and alternate contact of relay N² and the contact of release relay 31 to ground. Relay N² in opening its normal contact introduces a break in the energizing and holding circuit of relay K¹ and in closing its right-hand alternate contact causes the operation of relays K² and M² over a circuit from battery through the windings of these relays in parallel, right-hand alternate contact of relay N² and normal contacts of other relays N³ to N¹⁶ inclusive to ground provided none of the latter relays have been previously energized due to the respective lines being in signal initiating condition. Relay K² in operating opens the energizing circuits of relays N³ to N¹⁶ inclusive to prevent energization thereof while the line L² is in signal initiating condition. If relay N¹ were energized during this time, relays K¹ and M¹ would fail to energize due to the energization of relay N². Relays of the K group may be slow in releasing so that upon the deenergization of the relays of a set the normal contact of the N relay thereof will be closed prior to the closure of the contact of the K relay. In this manner it is insured that the signals of the various lines which may be in signal originating condition simultaneously will be transmitted in a definite order, namely, beginning with the

highest numbered line and proceeding in a descending scale. After the signals corresponding to the lowest numbered line function, the code signal corresponding to the highest numbered line then in signal originating condition is transmitted.

Relay M^2 , which determines the code of the signal to be transmitted over the common signaling path P, upon being energized 10 closes its right-hand alternate contact, and grounds the signal control lead A^2 causing the energization of relay 24 over a circuit from battery through the right-hand alternate contact of relay 22, winding of relay 15 24, contact 32 thereof, signal control lead A^2 , right-hand alternate contact of relay M^2 and contacts of slow-release relay 33 and release relay 31 to ground. Signal control leads A^2 and B^2 are thereby rendered 20 ineffective until a subsequent deenergization of relay 24. Relay 24 upon being energized completes a locking circuit for itself from battery through the right-hand alternate contact of relay 22, winding of relay 24, 25 contact 34 thereof and the normal contact of relay 35 to ground. The opening of contact 30 of relay 24 opens the original energizing circuit of relay N^2 which together with relays K^2 and M^2 remain energized 30 due to the previously traced locking circuit through the left-hand winding of relay N^2 . The closure of the middle alternate contact of relay M^2 prepares a circuit for the storing relay 5 which however does not at this 35 time function. The closure of the left-hand alternate contact of relay M^2 causes the operation of storing relay 4 and start relay 36 over a circuit from battery through the windings of start relay 36 and storing relay 40 4 and the left-hand alternate contact of relay M^2 to ground.

The energization of storing relay 4 disconnects positive battery from individual sending segment 4 of the sending distributor TD 45 and connects negative battery thereto. It is to be observed that positive battery is now connected with the other individual sending segments 1, 2, 3 and 5. The closure of the contact of start relay 36 causes the 50 energization of release magnet TDM over a circuit from battery through ring 8, the brush arm and segment 11 of the sending distributor TD, contact of start relay 36 and the winding of release magnet TDM to ground. The release magnet TDM in attracting its armature releases the brush arm of the sending distributor TD which thereupon makes a complete revolution in a clockwise direction successively engaging the 55 various segments thereof. Normally the outer half of the brush arm connects negative battery through segment r , the brush arm, the common sending ring 14 with the common signaling path P. Upon engagement of the brush arm with the starting seg-

ment s positive battery is connected with the common signaling path P thereupon causing the energization of the differential polarized relay 40' at the office Y. As the brush arm moves out of engagement with the segment 70 11, the release magnet TDM is deenergized restoring its armature to normal position so that it may stop the brush arm upon the completion of its cycle and hold it against rotation. The engagement of the brush arm with the segment 12 causes the operation of slow release relay 33 over a circuit from battery through ring 8 the brush arm, segment 12 and the winding of slow release relay 33 to ground. This relay 33 thereupon removes 80 ground from the signal control lead A^2 . As the brush arm successively engages the individual sending segments 1 to 5 inclusive, signaling current of the polarities connected therewith are successively connected with 85 the common signaling path P which terminates at the office X on the common sending ring 14. These polarities are such that the sending distributor TD transmits a code signal of five impulses, the first, second, third and fifth of which are positive and the fourth negative. When the brush arm moves out of engagement with the segment 90 12, the energizing circuit of the slow releasing relay 33 is opened, and upon the engagement of the brush arm with the segment 13, release relay 31 is energized over a circuit from battery through the ring 8, the brush arm, the segment 13 and the winding of release relay 31 to ground. Relay 33 is made 95 slow in releasing so that its contact remains open until after the opening of the contact of release relay 31, thereby to prevent the premature operation of any relay 24 of a 100 trunk line in signal initiating position. The energization of release relay 31 opens the locking circuit of relay N^2 which thereupon releases, causing the deenergization of relays M^2 and K^2 . Storing relay 4 and start 105 relay 36 release upon the opening of the left-hand alternate contact of relay M^2 . As the brush arms moves out of engagement with segment 13, release relay 31 is deenergized, and when the brush arm engages segment r , 110 negative signaling current is connected with the common signaling path P. The storing relays 1 to 5 and the sending distributor TD are now in normal condition ready for association with any other trunk line which 115 may initiate a signal at the office X. 120

Upon the energization of the differential polarized relay 40' due to the transmission of the first positive or starting impulse over the common signaling path P when the brush arm of the sending distributor TD engages its starting segment s , release magnet RDM' of the receiving distributor RD' is energized over a circuit from battery through the alternate contact of the differential polarized relay 40', segment 13', the brush arm 125 130

and segment 8' and the winding of the release magnet RDM' to ground. The attraction of the armature of the release magnet RDM' upon the energization thereof, releases the brush arm of the receiving distributor RD' which is thereupon rotated through a complete cycle at the end of which the brush arm is stopped in its normal position. As the brush arm moves out of engagement with the segments 13' and 8', the release magnet RDM' is deenergized permitting the release of its armature preparatory to stopping the brush arm when it reaches its normal position. When the brush arm moves out of engagement with the segments 11' and 12', relay 39' is deenergized and closes its contact which is common to the locking circuits of the locking relays 41' to 45' inclusive. The armature of the differential polarized relay 40' assumes its normal position when negative signaling current is connected with the other end of the common signaling path P and assumes its alternate position whenever positive current is connected with the opposite end of the common signaling path P. The brush arms of the sending and receiving distributors TD and RD' are being rotated at the same time and in synchronism. Therefore when the brush arm of the sending distributor TD engages the sending segment 4 to which negative signaling current is connected, the armature of the differential polarized relay 40' is in its normal position while the brush arm of the receiving distributor RD' engages the receiving segment 4'. Therefore locking relay 44' is energized over a circuit from battery through the normal contact of differential polarized relay 40', common receiving segment 10', the brush arm, individual receiving segment 4' and the upper winding of locking relay 44' to ground. Relay 44' immediately locks up over a circuit from battery through the contact of relay 39', the lower alternate contact of relay 44' and the lower winding thereof to ground.

Upon the subsequent engagement of the brush arm of the receiving distributor RD' with segments 6' and 7', signal receiving relay 55 operates over a circuit from negative battery through the normal contact of locking relay 45', segment 6', the brush arm and segment 7' of the receiving distributor RD', upper alternate contact of locking relay 44', the lower normal contacts of pyramid selecting relays 52', 51' and 49', signal receiving lead D'2 and the left-hand winding of signal receiving relay 55 to ground. Signal receiving relay 55 thereupon completes a locking circuit for itself from battery through its middle alternate contact and right-hand winding to ground; and causes the lighting of supervisory lamp 57 over a circuit from battery through the lamp 57, lower normal contact of relay 58 and the left-hand alternate contact of signal receiving relay 55 to ground. The lighting of this supervisory lamp 57 is an indication to the operator at the office Y that connection has been made with the proper trunk line, in this case trunk line L², 70 by the operator at the office X. The right-hand or energizing winding of signal receiving relay 75 is connected through the contact of slow-release relay 110 with the signal receiving lead D'2 and therefore in parallel with the left-hand or energizing winding of signal receiving relay 55, so that signal receiving relay 75 is energized at the same time as signal receiving relay 55. This signal receiving relay 75 does not however lock up, for its locking circuit is open at the contact of the slow-release relay 74. Therefore the energization of signal receiving relay 75 at this time performs no useful function. When the brush arm of the receiving distributor RD' moves out of engagement with the segments 6' and 7', energizing circuits of signal receiving relays 55 and 75 are opened, causing the deenergization of signal receiving relay 75. When the brush arm engages the segments 8' and 13' the armature of differential polarized relay 40' is in its normal position, for the brush arm of the sending distributor TD is now in engagement with segment r and negative signaling current is connected with the common signaling path P. The energizing circuit of the release magnet RDM' is therefore open at this time. The engagement of the brush arm with the segments 11' and 12' causes the energization of relay 39' which thereupon opens the locking circuit of relay 44'. The receiving equipment at the office Y is now in normal condition ready for receiving any further transmitted code signals resulting from signals initiated by any other trunk lines at the office X.

Connection of toll switching trunk circuit H with telephone line G.

At the time the operator at the office Y designated the trunk line with which the operator at the office X should connect the cord circuit F, the operator at the office Y also communicated with the office Z over an order wire circuit (not shown) advising the operator thereat the number of the desired line, whereupon the operator at the office Z designates the toll switching trunk circuit over which connection should be established. Assuming the toll switching trunk circuit H to be that designated, the operator at the office Z after designating this trunk circuit, inserts plug 60 of the toll switching trunk circuit H into jack 61 of the telephone line G. Relay 62 and cut-off relay 63 thereupon operate over a circuit from battery through the winding of relay 62, sleeve contacts of the plug 60 and the jack 61 and the winding of cut-off relay 63 to ground. The energiza- 130

tion of relay 62 causes supervisory lamp 64 to be lighted over a circuit from battery through the lamp 64, lower alternate contact of relay 62, resistance 65 and the normal contact of relay 66 to ground. The operation of the cut-off relay 63 disconnects the line relay 67 from the line wires of the telephone line G.

10 *Connection of trunk line L² with toll switching trunk circuit H.*

The operator at office Y observing the lighted condition of the lamp 57 inserts plug 70 of trunk line L² into jack 71 of the toll 70 switching trunk circuit H. Relay 72 thereupon operates over a circuit from battery through the jack 71 and resistance 73 to ground. Relays 58 and 74 thereupon operate, the former over a circuit from battery 15 through the contact of relay 72 and the winding of relay 58 to ground, and the latter over a circuit from battery through the contact of relay 72, winding of slow-release relay 74 and the normal contact of signal receiving relay 75 to ground. Relay 74, in operating prepares a temporary holding circuit for the signal receiving relay 75, the function of which will more fully hereinafter appear. The operation of relay 58 opens the circuit 20 and extinguishes the supervisory lamp 57. In closing its upper alternate contact relay 58 causes the operation of supervisory relays 56 and 66 over a circuit from battery through the left-hand winding of supervisory relay 25 66, left-hand normal contact of relay 76, tip contacts of the jack 71 and the plug 70, upper alternate contact of relay 58, upper normal contact of ringing relay 77, winding of supervisory relay 56, right-hand alternate 30 contact of signal receiving relay 55, lower normal contact of ringing relay 77, ring contacts of the plug 70 and the jack 71, the right-hand normal contact of relay 76 and the right-hand winding of supervisory relay 66 to ground. Supervisory relay 66, in operating, opens the circuit of and extinguishes the supervisory lamp 64.

The energization of supervisory relay 56 causes the energization of slow-release relays 78 and 79 over a circuit battery through the winding of these two relays in parallel and the alternate contact of supervisory relay 56 to ground. The opening of the left-hand normal contact of relay 78 causes the deenergization of a normally energized relay 24', which then causes the operation of relays in N'², K'² and M'² of the sending equipment SE'. The operation of the relay M'² causes the energization of relay 24' over 55 a circuit including signal control lead A'². Upon the energization of relay 24' it locks up over a circuit from battery through its winding, contact 34', alternate contact of relay 78 and alternate contact of the energized relay 79 to ground. At the time of

the operation of relay M'² of the sending equipment SE', start relay 36' and storing relay 4' thereof were operated. Storing relay 4' causes negative current to be connected with the individual sending segment 70 4' of the sending distributor TD' of the sending equipment SE'. Upon the operation of the start relay 36' the sending distributor TD' functions to transmit over the common signaling path P, a starting positive impulse followed by a code signal of 5 impulses the first, second, third and fifth of which are positive and the fourth negative. The storing relay 4', signal control 80 relays K'², M'² and N'² and the sending distributor TD' and other control apparatus of the sending equipment SE', after the transmission of the code signal, is restored to normal condition.

The transmitted starting impulse and the code signal being received at the office X, the differential polarized relay 40 cooperates with the receiving distributor RD, of the receiving equipment RE to select the signal receiving lead D² and to transmit 90 thereover a negative impulse which traverses the left-hand winding of and energizes the signal receiving relay 28. The signal receiving relay 28 upon being energized locks up over a circuit from battery through its right-hand alternate contact and right-hand winding to ground. Following the energization of signal receiving relay 28, all apparatus of the receiving equipment RE is restored to normal condition, ready to receive any other transmitted code signals originating at the office Y. The energization of this signal receiving relay 28 connects resistance 86 in parallel with the winding of relay 22, thereby lowering the 95 resistance of the circuit of supervisory lamp 23 to such an extent that the lamp becomes illuminated. This lighted lamp now serves as a signal to the operator at the office X, indicating that the connection has been completed through to the line of the wanted subscriber, and that the established circuit 100 is in condition for signaling the subscriber of the wanted line. The opening of the normal contact of signal receiving relay 28 causes the deenergization of relay 26 which upon releasing its armature connects the 105 energizing winding of signal receiving relay 27 with the receiving conductor D².

110 *Operator at office X actuates ringing key.*

The operator at office X upon observing the lighted condition of the supervisory lamp 23 may actuate ringing key 87 which connects the source of ringing current 88 with the talking conductors of the cord circuit F and the trunk line L². Relay 89 is operated by current from the source 88, 115 causing the energization of slow-release relay 35. The slow-release relay 35 in closing 120

125

130

its upper and middle contacts short-circuits the left-hand windings of repeating coil 90, connecting the ringing response relay 89 to the talking conductors of the trunk line L^2 , 5 independent of these windings of the repeating coil. The short-circuiting of these windings of the repeating coil prevents the flow of ringing current beyond the repeating coil, which might affect apparatus connected with the trunk line beyond this repeating coil. The opening of the normal contact of relay 35 causes the deenergization of the relay 24 in the manner previously described in connection with the insertion of 10 the plug 20 within the jack 21. The closure of the lower alternate contact of relay 35 causes the energization of slow-release relay 91. Relays N^2 , K^2 and M^2 operate and lock up upon the deenergization of relay 24. 15 The operation of relay M^2 causes the energization of relay 24 which thereupon locks up over a circuit from battery through the right-hand alternate contact of relay 22, winding of relay 24, contact 34 thereof and 20 the left-hand contact of slow-release relay 91 to ground. The energization of this slow-release relay 91 also opens its right-hand contact which disconnects resistance 86 from parallel relation with the winding 25 of relay 22, thereby increasing the resistance in circuit with the lamp 23 which then ceases to glow. Therefore during the operation of the ringing key 87 the supervisory lamp 23 is extinguished. 30 The operation of relay M^2 also causes the operation of storing relay 4 and starting relay 36 in the manner hereinbefore described. The sending distributor TD thereupon functions to transmit over the common signaling path P , a code signal of five impulses, the first, second, third, and fifth of which are positive and the fourth negative. After the transmission of this code signal, the sending distributor TD, its control apparatus, storing relay 4 and control relays K^2 , M^2 and N^2 are restored to normal condition. 35 The code signal is received at the office Y causing the differential polarized relay 40' connected in the common signaling path P , and the receiving distributor RD' controlled by and cooperating with the relay 40' to function in the manner hereinbefore described to select the signal receiving lead 45 D'^2 and to transmit thereover a negative impulse. The receiving equipment is then restored to normal condition. This negative impulse transmitted over the signal receiving lead D'^2 traverses the left-hand winding of and energizes the signal receiving relay 75. The polarity of this impulse being the same as the original energizing impulse of receiving relay 55 it does not affect the condition of this signal receiving 60 relay which therefore remains locked up. The signal receiving relay 75, upon energization, completes a locking circuit from battery through the contact of relay 74 and the left-hand alternate contact and winding of signal receiving relay 75 to ground. The closure of the left-hand alternate contact of signal receiving relay 75 causes the energization of slow-release relay 95, whereupon ringing relay 77 and slow-release relay 96 are immediately energized. The slow-release relay 96 in closing its alternate contact establishes a substitute holding circuit for relay 24' which may be traced from battery through the winding of relay 24', contact 34' thereof and the alternate contact of relay 96 to ground. Signal receiving relay 75, upon energization, opens the energizing circuit of slow-release relay 74 so that this slow-release relay 74 immediately begins to release its armature. Upon the full release of the armature of slow release relay 74 the locking circuit of signal receiving relay 75 is opened, releasing this relay. Then upon the opening of the right-hand alternate contact of signal receiving relay 75 the energizing circuit of slow-release relay 95 is opened. The full release of the armature of relay 95 opens the energizing circuits of ringing relay 77 and slow-release relay 96. Relay 96 was made slow in releasing so that its alternate contact will not be opened until after the energization of supervisory relay 56 following the release of ringing relay 77 as will more fully appear in next but one succeeding paragraph. Relays 74 and 95 are made slow in releasing so as to prolong the length of time that the ringing relay 77 is energized, and therefore the length of time that ringing current is connected with the incoming end of the trunk line L^2 . 105 Upon the energization of ringing relay 77 as before described, the normal contacts of this relay are opened causing the release of supervisory relay 56, which causes the release of relays 78 and 79. Relay 24' is not deenergized by the release of relays 56, 78 and 79 for its circuit is maintained at the closed alternate contact of relay 96. Relay 78 is made slow in releasing so that it will not release its armature during the short intervals that the alternate contact of supervisory relay may be opened when the called subscriber is rapidly opening and closing the switchhook contact, as will more fully hereinafter appear. Relay 79, however, releases its armature upon each opening of the alternate contact of relay 56, said relay 79 being made only slightly slow to release. The closure of the upper alternate contact of relay 77 completes a holding circuit for relay 66 which may be traced from battery through the left-hand winding of relay 66, left-hand normal contact of relay 76, tip contacts of the jack 71 and the plug 70, the upper alternate contact of relay 58 120 125 130

and the upper alternate contact of ringing relay 77 to ground. The closure of the lower alternate contact of ringing relay 77 causes the operation of ringing response relay 98 over a circuit from the source of ringing current 97, through the lower alternate contact of ringing relay 77, ring contacts of the plug 70 and the jack 71, winding of ringing response relay 98, the condenser in series therewith, tip contacts of the jack 71 and the plug 70, upper alternate contact of relay 58 and the upper alternate contact of ringing relay 77 to ground. Relay 98 in operating causes the operation of relay 76 and ringing relay 99 over a circuit from battery through the left-hand winding of relay 76, winding of relay 99 and the contact of ringing response 98 to ground. Relay 76 in operating opens the temporary holding circuit of relay 66 but before doing this establishes another holding circuit therefor which may be traced from battery through the left-hand winding of relay 66 and the alternate contact of relay 76 to ground. Relay 76 in opening its normal contacts disconnects relay 66 from the talking conductors of the toll switching trunk circuit H while ringing current is connected therewith. The energization of ringing relay 99 connects the source of ringing current 100 with the telephone line G to cause the operation of the usual call bell at the station.

Upon the deenergization of the ringing relay 77 in the manner hereinbefore described ringing current is disconnected from the incoming end of the trunk line L², whereupon relays 98, 76 and 99 release their armatures. The release of ringing relay 99 disconnects ringing current from the called line while the release of relay 76 in connection with the release of the ringing relay 77 causes the energization of supervisory relay 56, relay 66 being maintained energized over the circuit which energizes supervisory relay 56. The energization of supervisory relay 56 causes the reenergization of relays 78 and 79 in the manner hereinbefore described. The energizing circuit of relay 96 is opened at the same time as that of ringing relay 77, but is made slow in releasing, so that the holding or locking circuit of relay 24' including the alternate contact of relay 96 is not opened until after another holding or locking circuit therefor is established through the alternate contacts of relays 78 and 79. Relay 24' is therefore not affected when ringing on the wanted line.

60 *Operator at office X restores ringing key.*

Upon the restoration of the ringing key 87 to normal position relay 89 deenergizes causing the release of slow release relay 35 which removes the short-circuit of the left-

hand windings of the repeating coil 90 and opens the energizing circuit of slow-release relay 91. Relay 91 is made slow in releasing so as to insure that the locking circuit of relay 24 will be maintained closed at the left-hand contact of relay 91 until after closure of the normal contact of relay 35 which is in parallel relation therewith. Upon the closure of the right-hand contact of relay 91, resistance 86 is again connected in parallel with the winding of relay 22, thereby lowering the resistance in circuit with and permitting the supervisory lamp 23 to glow.

65 *Subscriber of telephone line G removes receiver from switchhook.*

The subscriber at the station on telephone line G in responding to the operation of the call bell thereat removes the receiver from the switchhook thereby causing the operation of supervisory relay 105 over a circuit from battery through the winding of supervisory relay 105, upper normal contact of ringing relay 99, ring contacts of the plug 60 and the jack 61, out over one side of the line, through the substation apparatus and back over the other side of the line, tip contacts of the jack 61 and the plug 60, upper alternate contact of relay 62 and lower normal contact of ringing relay 99 to ground. Supervisory relay 105 in operating causes the energization of relay 76 over a circuit from battery through the left-hand winding of relay 76, contact of supervisory relay 105, right-hand winding of relay 76 and the alternate contact of relay 66 to ground. Relay 76 in operating closes its alternate contact and opens its normal contacts whereby relay 66 is disconnected from the circuit including the supervisory relay 56, and is maintained energized through its left-hand winding and the alternate contact of relay 76. Relay 76 in operating also causes the deenergization of supervisory relay 56. Relay 96 is not now energized so that the deenergization of relay 78 following the deenergization of supervisory relay 56 opens the locking circuit of relay 24' which thereupon releases its armatures. Battery is now connected with the signal control leads B'2 and C'2 extending to the sending equipment SE'. Relay N'2 of the sending equipment SE' is energized over the signal control lead B'2 and locks up causing the energization of relays M'2 and K'2 of sending equipment SE'. The energization of relay M'2 in addition to causing the energization of start relay 36' and storing relay 4' also causes the energization of storing relay 5' of this sending equipment SE' which is energized through a contact of relay M'2 and over the leads C'2 and right-hand normal contact of relay 78. Positive signaling current is now

connected with individual sending segments 1', 2' and 3' and negative signaling current with the individual sending segments 4' and 5' of the sending distributor TD' of the sending equipment SE' so that a code signal of five impulses, the first three of which are positive and the last two negative is transmitted over the common signaling path P by the sending distributor TD'. When the brush of the distributor associated with the sending equipment SE' reaches its normal position after transmitting the code signal all apparatus associated with the sending equipment SE' is restored to normal position and relay 24' is locked up. The transmitted code signal being received at the office X causes the differential polarized relay 40 and the receiving distributor RD of the receiving equipment to cooperate whereby the signal receiving lead D² is selected by the first four impulses of the code signal, and the fifth impulse of the code signal causes the energization and locking up of the pole changing locking relay 45. The relay 45 upon energizing cooperates with the receiving distributor RD to transmit a positive impulse over the selected signal receiving lead D² which traverses the left-hand winding of signaling receiving relay 28 and the right-hand winding of signal receiving relay 27. The relation of the windings of the signal receiving relay 28 is such that upon the flow of positive current through its left-hand winding, when it is locked up through its right-hand winding the relay is differentialized and releases its armatures. Signal receiving relays 27 and 28 are alike, so that the flow of positive current through its right-hand winding energizes the same but the closure of its locking circuit upon energization, causes this relay 27 to be differentialized, and release its armatures. Receiving relay 28 in releasing its armatures opens the circuit through resistance 86, thereby removing this resistance from parallel relation with the winding of relay 22, causing an increase in the resistance of the circuit of the supervisory lamp 23 which now ceases to glow. The closure of the normal contact of signal receiving relay 28 causes the energization of slow release relay 26 which opens its contact, disconnecting the energizing winding of signal receiving relay 27 from the receiving conductor or lead D². The extinguishment of the supervisory lamp 23 serves as a signal to the operator indicating that the called subscriber has answered.

It is to be observed that the apparatus at the office X is now in the same condition that it was following the transmission of the code signal over the signaling path P resulting from the origination of the signal at this office by the insertion of the plug 20 of the cord circuit F into the jack 21 of the trunk

line L². Hence all relays at the office X are deenergized with the exception of relays 22, 24, 25 and 26 and relay 39 of the receiving equipment RE' which corresponds to relay 39' of the receiving equipment located at the office Y. 70

At this time the following relays at the office Y are energized: signal receiving relay 55, relays 72, 58, 24' and 74, and relay 39' associated with the receiver distributor RD', 75 while at the office Z relays 62, 63, 66, 76 and 105 are energized.

Subscriber restores receiver to the switchhook. 80

At the conclusion of the conversation the subscriber at the station on telephone line G restores the receiver to the switchhook, whereupon supervisory relay 105 deenergizes, opening the circuit of and deenergizing relay 76. Relay 66 is thereupon connected in circuit with supervisory relay 56 causing the energization of this supervisory relay 56 which closes the circuits of and energizes relays 78 and 79. Upon the opening of the left-hand normal contact of relay 78, relay 24' is deenergized connecting battery with signal receiving lead B². The connection of battery with the signal control lead B² causes the sending distributor TD' of the sending equipment SE' to transmit over the signal path P a code signal of five impulses, the first, second, third and fifth of which are positive and the fourth negative. Following the transmission of this code signal relay 24' is locked up in the manner before described and the apparatus of the sending equipment SE' is restored to normal condition. 95

This transmitted code signal is received at the office X by the receiving equipment RE, which selects the signal receiving lead D² and transmits thereover a negative impulse which traverses the left-hand winding of and energizes signal receiving relay 28. Signal receiving relay 28 locks up causing the release of slow-release relay 26 which connects the energizing winding of signal receiving relay 27 with the signal receiving lead D². Signal receiving relay 28 in closing its left-hand alternate contact connects ground with the resistance 86, thereby including this resistance in parallel relation with the winding of relay 22. The supervisory lamp 23 is thereupon lighted to furnish disconnect signal to the operator at the office X. 110 115 120

Operator at office X disconnects cord circuit F from trunk line L². 125

The operator at office X upon observing the lighted condition of the supervisory lamp 23 withdraws the plug 20 from the jack 21, causing the release of relays 22, 130

24 and 25. The deenergization of relay 22 connects the battery with signal control lead C² while the deenergization of relay 24 connects battery with the signal control lead B². Relays K², M² and N² then operate in the manner hereinbefore described and upon the operation of relay M², restoring lead A² is grounded to energize relay 24 which then locks up through the right-hand normal contact of relay 22, winding of relay 24, contact 34 thereof and the normal contact of relay 35 to ground. The operation of relay M² also causes the operation of start relay 36 and storing relay 4 in the manner hereinbefore described and in addition causes the operation of storing relay 5 over a circuit from battery through the left-hand normal contact of relay 22, signal control lead C², middle alternate contact of relay M² and the winding of storing relay 5 to ground.

The sending distributor TD thereupon functions to transmit over the signaling path P a code signal comprising three positive impulses followed by two negative impulses. This code signal being received at the office Y, the differential polarized relay 40' and the receiving distributor RD' cooperate to cause the selection of signal receiving lead D'² and the energization and locking up of relay 45' which cooperates with the receiving distributor RD' to transmit a positive impulse over the selected signal receiving lead D'². This positive impulse traverses the left-hand winding of signal receiving relay 55 which is thereby differentialized and releases its armatures. This positive impulse traverses the right-hand winding of and energizes signal receiving relay 75, but this relay is immediately differentialized by the closure of its left-hand contact and releases its armatures. The opening of the right-hand alternate contact of signal receiving relay 55 opens the circuit of supervision relays 56 and 66 which thereupon release their armatures. The closure of the normal contact of signal receiving relay 55 causes supervisory lamp 57 to be lighted over a circuit from battery through the lamp 57, lower alternate contact of relay 58 and the normal contact of signal receiving relay 55 to ground. Slow-release relay 110 is also energized over a circuit from battery through the middle alternate contact of relay 58, winding of relay 110 and the normal contact of signal receiving relay 55 to ground. Relay 110 thereupon opens its contact, disconnecting the energizing winding of signal receiving relay 75 from the signal receiving lead D'². This relay 110 is provided and is made slow in releasing, so that if the plug 70 is inserted in the jack 71 before the plug 20 is inserted in the jack 21, relay 110 will be energized, to prevent the false operation

of signal receiving relay 75, when the first negative impulse is transmitted over signal receiving lead D'² due to the insertion of the plug 20 in the jack 21. The release of relay 66 causes supervisory lamp 64 to be lighted over a circuit from battery through the lamp 64, lower alternate contact of relay 62, resistance 65 and the normal contact of relay 66 to ground. The supervisory lamps 57 and 64 in lighting serve as disconnect signals to the operators at the offices Y and Z respectively.

Upon the deenergization of supervisory relay 56 following the release of signal receiving relay 55 in the manner previously described, relays 78 and 79 release their armatures causing the deenergization of relay 24'. Relay 24' thereupon connects battery to signal control lead B'², while relay 78 connects battery to signal control lead C². The sending equipment SE' thereupon functions to ground the restoring lead A'² energizing relay 24' which thereupon locks up. The sending distributor TD' transmits over the common signaling path P a code signal consisting of three positive impulses followed by two negative impulses.

This code signal being received by the receiving equipment RE at the office X, selects the signal receiving lead D² and transmits thereover a positive impulse which traverses the left-hand winding of and energizes the signal receiving relay 28. Signal receiving relay 28 is at this time locked up so that this positive impulse through its left-hand winding renders the relay differential and it releases its armatures, whereupon all apparatus at the office X is restored to its normal condition, the only energized relays being relay 24, and relay 39 of the receiving RE.

The operators at the offices Y and Z upon observing the lighted condition of the respective supervisory lamps 57 and 64 withdraw the plugs 70 and 60 from the respective jacks 71 and 61, thereby restoring all apparatus at these two offices to normal condition. At this time the only energized relays at the office Y are relays 24' and 39', while there are no energized relays at the office Z.

Subscriber at station on telephone line G recalls operator at office X.

Should the subscriber at the station on the telephone line G, after answering a call when connection is established between the toll cord circuit F and the telephone line G by way of trunk line L² and the toll switching trunk circuit H, wish to signal the operator at the office X, this may be done by repeatedly opening and closing the switchhook contact at the station on telephone line G. The first opening of the switchhook contact causes the sending distributor TD' of

connected with individual sending segments 1', 2' and 3' and negative signaling current with the individual sending segments 4' and 5' of the sending distributor TD' 5 of the sending equipment SE' so that a code signal of five impulses, the first three of which are positive and the last two negative is transmitted over the common signaling path P by the sending distributor TD'. When the brush of the distributor associated with the sending equipment SE' reaches its normal position after transmitting the code signal all apparatus associated with the sending equipment SE' is restored 10 to normal position and relay 24' is locked up. The transmitted code signal being received at the office X causes the differential polarized relay 40 and the receiving distributor RD of the receiving equipment to cooperate 20 whereby the signal receiving lead D² is selected by the first four impulses of the code signal, and the fifth impulse of the code signal causes the energization and locking up of the pole changing locking relay 45. The relay 45 upon energizing cooperates 25 with the receiving distributor RD to transmit a positive impulse over the selected signal receiving lead D² which traverses the left-hand winding of signaling receiving relay 28 and the right-hand winding of signal receiving relay 27. The relation of the windings of the signal receiving relay 28 is such that upon the flow of positive current through its left-hand winding, when it is 30 locked up through its right-hand winding the relay is differentialized and releases its armatures. Signal receiving relays 27 and 28 are alike, so that the flow of positive current through its right-hand winding energizes the same but the closure of its locking circuit upon energization, causes this relay 27 to be differentialized, and release its armatures. Receiving relay 28 in releasing its armatures opens the circuit through resistance 86, thereby removing this resistance 40 from parallel relation with the winding of relay 22, causing an increase in the resistance of the circuit of the supervisory lamp 23 which now ceases to glow. The closure 45 of the normal contact of signal receiving relay 28 causes the energization of slow release relay 26 which opens its contact, disconnecting the energizing winding of signal receiving relay 27 from the receiving 50 conductor or lead D². The extinguishment of the supervisory lamp 23 serves as a signal to the operator indicating that the called subscriber has answered.

It is to be observed that the apparatus at 60 the office X is now in the same condition that it was following the transmission of the code signal over the signaling path P resulting from the origination of the signal at this office by the insertion of the plug 20 of the 65 cord circuit F into the jack 21 of the trunk

line L². Hence all relays at the office X are deenergized with the exception of relays 22, 24, 25 and 26 and relay 39 of the receiving equipment RE' which corresponds to relay 39' of the receiving equipment located 70 at the office Y.

At this time the following relays at the office Y are energized: signal receiving relay 55, relays 72, 58, 24' and 74, and relay 39' associated with the receiver distributor RD', 75 while at the office Z relays 62, 63, 66, 76 and 105 are energized.

Subscriber restores receiver to the switchhook. 80

At the conclusion of the conversation the subscriber at the station on telephone line G restores the receiver to the switchhook, whereupon supervisory relay 105 deenergizes, opening the circuit of and deenergizing relay 76. Relay 66 is thereupon connected in circuit with supervisory relay 56 causing the energization of this supervisory relay 56 which closes the circuits of and energizes relays 78 and 79. Upon the opening of the left-hand normal contact of relay 78, relay 24' is deenergized connecting battery with signal receiving lead B'². The connection of battery with the signal control lead B'² causes the sending distributor TD' of the sending equipment SE' to transmit over the signal path P a code signal of five impulses, the first, second, third and fifth of which are positive and the fourth negative. Following the transmission of this code signal relay 24' is locked up in the manner before described and the apparatus of the sending equipment SE' is restored to normal condition. 90

This transmitted code signal is received at the office X by the receiving equipment RE, which selects the signal receiving lead D² and transmits thereover a negative impulse which traverses the left-hand winding of and energizes signal receiving relay 28. Signal receiving relay 28 locks up causing the release of slow-release relay 26 which connects the energizing winding of signal receiving relay 27 with the signal receiving lead D². Signal receiving relay 28 in closing its left-hand alternate contact connects ground with the resistance 86, thereby including this resistance in parallel relation with the winding of relay 22. The supervisory lamp 23 is thereupon lighted to furnish disconnect signal to the operator at the office X. 105

Operator at office X disconnects cord circuit F from trunk line L². 110

The operator at office X upon observing the lighted condition of the supervisory lamp 23 withdraws the plug 20 from the jack 21, causing the release of relays 22, 115 120 130

24 and 25. The deenergization of relay 22 connects the battery with signal control lead C² while the deenergization of relay 24 connects battery with the signal control lead B². Relays K², M² and N² then operate in the manner hereinbefore described and upon the operation of relay M², restoring lead A² is grounded to energize relay 24 which then locks up through the right-hand 5 normal contact of relay 22, winding of relay 24, contact 34 thereof and the normal contact of relay 35 to ground. The operation of relay M² also causes the operation of start relay 36 and storing relay 4 in the 10 manner hereinbefore described and in addition causes the operation of storing relay 5 over a circuit from battery through the left-hand normal contact of relay 22, signal control lead C², middle alternate contact of relay M² and the winding of storing relay 5 to ground.

The sending distributor TD thereupon functions to transmit over the signaling path P a code signal comprising three positive impulses followed by two negative impulses. This code signal being received at the office Y, the differential polarized relay 40' and the receiving distributor RD' cooperate to cause the selection of signal receiving lead D'² and the energization and locking up of relay 45' which cooperates with the receiving distributor RD' to transmit a positive impulse over the selected signal receiving lead D'². This positive impulse traverses the left-hand winding of signal receiving relay 55 which is thereby differentialized and releases its armatures. This positive impulse traverses the right-hand winding of and energizes signal receiving relay 75, but this relay is immediately differentialized by the closure of its left-hand contact and releases its armatures. The opening of the right-hand alternate contact of signal receiving relay 55 opens 40 the circuit of supervision relays 56 and 66 which thereupon release their armatures. The closure of the normal contact of signal receiving relay 55 causes supervisory lamp 57 to be lighted over a circuit from battery through the lamp 57, lower alternate contact of relay 58 and the normal contact of signal receiving relay 55 to ground. Slow-release relay 110 is also energized over a circuit from battery through the middle 45 alternate contact of relay 58, winding of relay 110 and the normal contact of signal receiving relay 55 to ground. Relay 110 thereupon opens its contact, disconnecting the energizing winding of signal receiving relay 75 from the signal receiving lead D'². This relay 110 is provided and is made slow in releasing, so that if the plug 50 50 is inserted in the jack 71 before the plug 20 is inserted in the jack 21, relay 110 will be energized, to prevent the false operation

of signal receiving relay 75, when the first negative impulse is transmitted over signal receiving lead D'² due to the insertion of the plug 20 in the jack 21. The release of relay 66 causes supervisory lamp 64 to 70 be lighted over a circuit from battery through the lamp 64, lower alternate contact of relay 62, resistance 65 and the normal contact of relay 66 to ground. The supervisory lamps 57 and 64 in lighting 75 serve as disconnect signals to the operators at the offices Y and Z respectively.

Upon the deenergization of supervisory relay 56 following the release of signal receiving relay 55 in the manner previously described, relays 78 and 79 release their armatures causing the deenergization of relay 24'. Relay 24' thereupon connects battery to signal control lead B'², while relay 78 connects battery to signal control lead C². The sending equipment SE' thereupon functions to ground the restoring lead A'² energizing relay 24' which thereupon locks up. The sending distributor TD' transmits over the common signaling path P a code signal consisting of three positive impulses followed by two negative impulses.

This code signal being received by the receiving equipment RE at the office X, selects the signal receiving lead D² and transmits thereover a positive impulse which traverses the left-hand winding of and energizes the signal receiving relay 28. Signal receiving relay 28 is at this time locked up so that this positive impulse through its left-hand winding renders the relay differential and it releases its armatures, whereupon all apparatus at the office X is restored to its normal condition, the only energized relays being relay 24, and relay 39 of the receiving RE.

The operators at the offices Y and Z upon observing the lighted condition of the respective supervisory lamps 57 and 64 withdraw the plugs 70 and 60 from the respective jacks 71 and 61, thereby restoring all apparatus at these two offices to normal condition. At this time the only energized relays at the office Y are relays 24' and 39', while there are no energized relays at the office Z.

Subscriber at station on telephone line G recalls operator at office X.

Should the subscriber at the station on the telephone line G, after answering a call when connection is established between the toll cord circuit F and the telephone line G by way of trunk line L² and the toll switching trunk circuit H, wish to signal the operator at the office X, this may be done by repeatedly opening and closing the switchhook contact at the station on telephone line G. The first opening of the switchhook contact causes the sending distributor TD' of 130

- the sending equipment SE' to transmit over the signaling path P a code signal of five impulses the first three of which are positive, the fourth negative and fifth positive. This 5 code signal being received at the office X , receiving equipment RE causes a negative impulse to be transmitted over the signal receiving conductor D^2 . Signal receiving relay 28 thereupon energizes and locks up.
- 10 The energization of signal receiving relay 28 causes the deenergization of relay 26 and the lighting of lamp 23. In connection with the transmission of this code signal it will be recalled that supervisory relay 56 was 15 energized by the opening of the switchhook contact and upon being energized caused the energization of relays 78 and 79. When recalling the operator at the office X the subscriber at the station on telephone line G 20 rapidly opens and closes the switchhook contact. The speed of opening and closing this contact is such that supervisory relay 56 is energized upon each opening and de-energized upon each closure of this switchhook contact. Relay 79, which is only slightly slow in releasing and faster than relay 78, 25 is energized upon each energization of supervisory relay 56 and is deenergized upon each deenergization thereof, but relay 78 is slower 30 in releasing so that during the short interval that supervisory relay 56 may be deenergized by the closure of the switchhook contact during the time the subscriber is rapidly opening and closing this contact, relay 78 maintains 35 its normal contacts open and its alternate contact closed thus preventing the application of battery to the disconnect lead C^2 . Upon the first closure of the switchhook contact following the opening thereof, 40 relay 79 releases its armature, but the contact of relay 79 is not opened until after the closure of the normal contact of supervisory relay 56 whereby relay 24' remains locked up. The normal contact of supervisory relay 56 therefore controls relay 24' 45 while the subscriber is rapidly opening and closing the switchhook contact to recall the operator at the office X . Upon each subsequent opening of the switchhook contact and 50 consequent energization of relay 56 while the subscriber is rapidly opening and closing this contact, relay 24' is deenergized, before relay 79 can respond to the closure of the alternate contact of relay 56, to cause 55 the sending distributor TD' to transmit a code signal of five impulses the first three being positive, the fourth negative and the fifth positive. Each such subsequently transmitted code signal being received at the 60 office X causes the receiving equipment RE to select signal receiving lead D^2 and to transmit thereover a negative impulse which energizes signal receiving relay 27. This signal receiving relay then locks up over a 65 circuit from battery through the contact of slow release relay 25 and the left-hand contact and winding of signal receiving relay 27 to ground. Slow-release relay 29 is energized upon the energization and locking up of signal receiving relay 27 and disconnects 70 ground from the resistance 86 and connects therewith grounded interrupter 111, so that the resistance 86 is intermittently connected in parallel with the winding of relay 22. Supervisory lamp 23 is thereupon intermittently lighted to furnish a signal to the operator at the office X , indicating that the subscriber at the station on telephone line G 75 is signaling.
- Upon the opening of the normal contact of signal receiving relay 27, due to the energization thereof, relay 25 begins to release, and when its armature is fully released the locking winding of signal receiving relay 27 is opened, so that this relay releases its armatures, opening the energizing circuit of slow-release relay 29. The speed at which the switchhook contact at the station on telephone line G is being opened and closed is such that another negative impulse is received over the signal receiving conductor D^2 , before slow release relay 29 can open its alternate contact, whereby signal receiving relay 27 is again energized and upon being 80 energized immediately reestablishes the energizing circuit of slow-release relay 29. 85 Therefore, by making relays 25 and 29 slow-releasing the interrupter 111 is maintained in operative relation to the resistance 86 so long as the subscriber at the station on telephone line G is rapidly opening and closing the switchhook contact to signal the operator at the office X . After repeatedly and rapidly opening and closing the switchhook contact to signal the operator, the subscriber ceases 90 such operation, leaving the switchhook contact closed, whereby supervisory relay 105 and relay 76 operate to cause the deenergization of supervisory relay 56. Upon the deenergization of this relay 56, relays 78 and 95 100 105 110 115 120 125 130
- 79 release their armatures, causing the deenergization of relay 24'. Relay 78 being deenergized, battery is now connected with signal control leads B^2 and C^2 , and the sending distributor TD' of the sending equipment SE' therefore transmits over the signaling path P a code signal of five impulses of which the first, second, third and fifth are positive and the fourth negative which upon being received at the office X causes the receiving equipment RE to select the signal receiving lead D^2 and to transmit a positive impulse thereover. This positive impulse traverses the left-hand winding of signal receiving relay 28 causing the relay to be differentialized, and it thereupon releases its armatures, disconnecting the intermittent ground from the resistance 86. The supervisory lamp 23 therefore ceases to glow.
- Had the subscriber ceased the rapid open-

ing and closing of switchhook contact by leaving the switchhook contact open, then no further code signals would be transmitted from the office Y over the signaling path P. 5 Consequently slow-release relay 29 would fully release its armature, substituting a continuous for the intermittent ground, thereby causing the supervisory lamp 23 to be continuously lighted to furnish a disconnect signal to the operator at the office X.

It will be apparent from the foregoing description that if the called subscriber should accidentally depress the switchhook and thereby cause a single momentary reciprocation thereof, a code signal would be transmitted, when the switchhook contacts are opened, which would light the lamp 23. Then, upon the closure of said contacts, another code signal would be transmitted,

20 the same as in the case when the subscriber first answers the call, to permanently extinguish said lamp since the relay 27 is not operated to cause the interrupter 111 to repeatedly flash the lamp unless the switchhook contacts are again opened within a predetermined period of time after the first opening thereof. In this manner, the operation of repeatedly flashing the lamp 23 is delayed until successive code signals are received to operate both relays 27 and 28.

The operations described above with reference to building up a connection with telephone line G over the trunk line L² and the breaking down of such a connection are 35 characteristic of those taking place in building up and breaking down a connection over any one of the trunk lines to which the signaling path P is common. The only essential difference in operation, so far as the establishment of connections over the different trunk lines is concerned, is that different code signals are employed for the different trunk lines, and different sets of relays K, M and N will be operated and the storing relays 40 will be operated in differing combinations to determine polarities connected with the individual sending segments of the sending distributors and the locking relays and pyramid selecting relays controlled on the receiving distributors will be operated in differing combinations to select the appropriate signal receiving leads and the signal associated therewith to be operated. While this invention is not limited to any particular arrangement of code signals, the codes shown 45 in the following table have been found to be very satisfactory for a total of sixteen trunk lines served by the same common signaling path. In this table, the numbers in the first column indicate the numbers assigned to the trunk lines, while the numbers in the remaining columns indicate the order of the negative impulses in each group of five. The number "0" appearing in the first line in 50 the second, third, fifth and seventh columns

of the table means that no negative impulses are transmitted.

Trunk line No.	Signals from office X to office Y.			Signals from office Y to office X.			70
	Guard	Ring	Disconnect	Receiver on hook	Receiver off hook	Flashing

What is claimed is:

1. In a telephone system, in combination, a plurality of transmission circuits and a signaling path common thereto extending between two stations, a signaling device at one station associated with a predetermined one of the transmission circuits, means at the other station responsive to rapid changes in the condition of the predetermined transmission circuit to transmit a succession of signals over the signaling path, a signal receiving relay at the one station responsive to the first transmitted signal, a second receiving relay thereat responsive to each subsequently transmitted signal, a holding circuit for the second signal receiving relay established upon each response thereof, and means controlled by the second signal receiving relay for causing the operation of the signaling device. 90

one of the transmission circuits, means at the other station responsive to rapid changes in the condition of the predetermined transmission circuit to transmit a succession of 5 signals over the signaling path, a signal receiving relay at the one station responsive to the first transmitted signal, a second receiving relay thereat responsive to each subsequently transmitted signal, a holding circuit 10 for the second signal receiving relay established upon each response thereof, interrupter mechanism, and a relay energized upon the response of the second signal receiving relay to connect the interrupter 15 mechanism in operative relation to the signaling device and to maintain such operative relation after the deenergization of the second receiving relay.

4. In a telephone system, in combination, 20 a plurality of transmission circuits and a signaling path common thereto extending between two stations, a signaling device at one station associated with a predetermined one of the transmission circuits, means at 25 the other station responsive to rapid changes in the condition of the predetermined transmission circuit to transmit a succession of signals over the signaling path, a signal receiving circuit at the one station, a signal receiving relay controlled over the signal receiving circuit and energized in response to the first transmitted signal, a local relay responsive to the energization of the signal receiving relay, a second signal receiving 30 relay connected with the signal receiving circuit by the response of the local relay and energized in response to the next transmitted signal to cause the operation of the signaling device.

40 5. In a telephone system, in combination, a plurality of transmission circuits and a signaling path common thereto extending between two stations, a signaling device at one station associated with a predetermined one of the transmission circuits, means at 45 the other station responsive to rapid changes in the condition of the predetermined transmission circuit to transmit a succession of signals over the signaling path, a signal receiving circuit at the one station, a signal receiving relay controlled over the signal receiving circuit and energized in response to the first transmitted signal, a local relay responsive to the energization of the signal 50 receiving relay, a second signal receiving relay connected with the signal receiving circuit by the response of the local relay and energized in response to the next transmitted signal to cause the operation of the signaling device, interrupter mechanism, and means controlled by the second signal receiving relay and cooperating with the first signal receiving relay to connect the interrupter mechanism in operative relation to the signaling device.

55 6. In a telephone system, in combination, a plurality of transmission circuits and a signaling path common thereto extending between two stations, a signaling device at one station associated with a predetermined one of the transmission circuits, means at the other station responsive to changes in the condition of the predetermined circuit to transmit signals over the signaling path, 60 a signal receiving circuit at the one station, a signal receiving relay having an energizing and a locking winding, means responsive to the first transmitted signal for causing current of one polarity to traverse the energizing winding, a circuit including the locking winding established upon the energization of the signal receiving relay, and means responsive to a subsequently transmitted signal for causing current of the 65 120 125 130

a plurality of transmission circuits and a signaling path common thereto extending between two stations, a signaling device at one station associated with a predetermined one of the transmission circuits, means at 70 the other station responsive to rapid changes in the condition of the predetermined transmission circuit to transmit a succession of signals over the signaling path, a signal receiving circuit at the one station, a signal receiving relay having an energizing winding permanently connected with the signal receiving circuit and controlled thereover and energized in response to the first transmitted signal, and a second signal receiving 75 relay connected with the signal receiving circuit by the energization of the first signal receiving relay and responsive to the next transmitted signal to cause the operation of the signaling device.

7. In a telephone system, in combination, a plurality of transmission circuits and a signaling path common thereto extending between two stations, a signaling device at one station associated with a predetermined one of the transmission circuits, means at 90 the other station responsive to rapid changes in the condition of the predetermined transmission circuit to transmit a succession of signals over the signaling path, a signal receiving circuit at the one station and a signal receiving relay having an energizing winding normally connected with the signal receiving circuit and controlled thereover and energized in response to the first transmitted signal, a second signal receiving relay connected with the signal receiving circuit by the energization of the first signal receiving relay and responsive to the next 95 100 transmitted signal to cause the operation of the signaling device, interrupter mechanism, and means controlled by the second signal receiving relay and cooperating with the first signal receiving relay to connect the interrupter mechanism in operative relation to the signaling device.

8. In a telephone system, in combination, a plurality of transmission circuits and a signaling path common thereto extending between two stations, a signaling device at one station associated with a predetermined one of the transmission circuits, means at the other station responsive to changes in the condition of the predetermined circuit to transmit signals over the signaling path, 110 a signal receiving circuit at the one station, a signal receiving relay having an energizing and a locking winding, means responsive to the first transmitted signal for causing current of one polarity to traverse the energizing winding, a circuit including the locking winding established upon the energization of the signal receiving relay, and means responsive to a subsequently transmitted signal for causing current of the 115 120 125 130

opposite polarity to traverse the energizing winding of the signal receiving relay, whereby the signal receiving relay is deenergized.

9. In a telephone system, in combination, a plurality of transmission circuits and a signaling path common thereto extending between two stations, a signal device at one station associated with a predetermined one of the transmission circuits, means at the other station responsive to changes in the condition of the predetermined transmission circuits to transmit signals over the signaling path, a signal receiving relay at the one station responsive to the first transmitted signal, a locking circuit therefor established upon the energization of the signal receiving relay, a second signal receiving relay at the one station responsive to a subsequently transmitted signal, the locking circuit of the first named signal receiving relay being unaffected by the response of the second signal receiving relay, a locking circuit for the second signal receiving relay established upon the energization thereof, and an operating circuit for the signaling device controlled by the second signal receiving relay and including a contact of the first signal receiving relay.

10. In a telephone system, in combination, a plurality of transmission circuits and a signaling path common thereto extending between two stations, means at one station responsive to a change in the condition of a predetermined one of the transmission circuits to transmit a signal over the signaling path, a signal receiving relay at the other station energized in response to the transmitted signal, a locking circuit for the signal receiving relay established upon the energization thereof, a ringing relay controlled by and energized upon the response of this signal receiving relay, and a third relay controlled by and controlling the locking circuit of the signal receiving relay to cause the energization of the ringing relay for a predetermined period.

11. In a telephone system, in combination, a plurality of transmission circuits and a signaling path common thereto extending between two stations, means at one station responsive to a change in the condition of a predetermined one of the transmission circuits to transmit a signal over the signaling path, a signal receiving relay at the other station energized in response to the transmitted signal, a locking circuit for the signal receiving relay established upon the energization thereof, a slow release relay energized responsive to the energization of the signal receiving relay, a ringing relay energized upon the response of the slow release relay, and a fourth relay whose energizing circuit is controlled by the signal receiving relay controlling the locking circuit thereof and cooperating with the slow re-

lease relay to determine the duration of the energization of the ringing relay.

12. In a telephone system, in combination, a plurality of transmission circuits and a signaling path common thereto extending between two stations, means at one station responsive to each change in the condition of a predetermined one of the transmission circuits to transmit a signal over the signaling path, a signal receiving circuit at the other station, a signal receiving relay thereat having an energized winding normally connected with the receiving circuit, means responsive to a transmitted signal to cause current of one polarity to traverse the energizing winding of the signal receiving relay, a locking circuit therefor established upon the energization thereof, means at said other station responsive to a subsequently transmitted signal to cause current of the opposite polarity to traverse the energizing winding of the signal receiving relay to cause the deenergization thereof, an extension circuit at said other station, and a signaling device thereat operated upon the energization of the signal receiving relay before the predetermined transmission circuit is connected with the extension circuit and again operated upon the deenergization of the signal receiving relay after the connection of the transmission circuit with the extension circuit.

13. In a telephone system, in combination, a plurality of transmission circuits and a signaling path common thereto extending between two stations, means at one station for transmitting over the signaling path code signals individual to the different transmission circuits, a set of relays at the one station for each transmission line comprising a first relay for determining the code of the signal to be transmitted, a second relay for determining the order in which the code determining relays are energized, and a third relay controlling the energization of the first and second relays of this set, and means controlled by the third relay for preventing the simultaneous operation of two order determining relays.

14. In a telephone system, in combination, a plurality of transmission circuits, a signaling path common thereto extending between two stations, means at one station for transmitting over the signaling path code signals individual to the different transmission circuits, a set of relays at the one station individual to each transmission circuit comprising a first relay for determining the code of the signal to be transmitted, a second relay for determining the order in which the coded signals are transmitted, and a third relay for preventing the simultaneous transmission of two signals.

15. In a telephone system, in combination, a plurality of transmission circuits and a

- signaling path common thereto extending between two stations, means at one station for transmitting over the signaling path code signals individual to the different transmission circuits, a set of relays at the one station individual to each transmission circuit comprising a relay for determining the code of the signal to be transmitted, a relay for determining the order in which the code determining relays are energized, and a relay controlled by a change in the condition of its associated transmission line, and energizing circuits for the first and second-mentioned relays controlled by the third.
16. In a telephone system, in combination, a plurality of transmission circuits and a signaling path common thereto extending between two stations, means at one station for transmitting over the signaling path code signals individual to the different transmission circuits, a set of relays individual to each transmission circuit located at the one station comprising a relay for determining the code of the signal to be transmitted, a relay for determining the order in which the code-determining relays are energized and a third relay energized in response to a change in the condition of its associated transmission line, and an energizing circuit for the third relay of one set controlled by an order-determining relay of another set.
17. In a telephone system, in combination, a plurality of transmission circuits and a signaling path common thereto extending between two stations, means at one station for transmitting over the signaling path code signals individual to the different transmission circuits, a set of relays individual to each of several of said transmission circuits comprising a relay for determining the code of the signal to be transmitted, a relay for determining the order in which the code determining relays are energized, and a relay responsive to a change in the condition of the transmission circuit to which it is individual and a circuit for each order-determining relay including contacts of a third-mentioned relay in another set.
18. The method wherein an operator's signal is operated when a subscriber recalls which comprises delaying the operation of said recall signal until a predetermined time interval after the first operation of the switchhook for recall purposes.
19. In a telephone system, the combination with a recall control circuit, a signal controlled thereby and means for closing said circuit, of means for delaying the operation of the recall signal a predetermined time interval after the closure of said circuit.
20. In a signaling system, a plurality of transmission lines, a signal path common thereto, a signaling device, means responsive to a change in the condition of one of said lines for operating said signaling device and means for intermittently operating said signaling device only in response to more than one change in the condition of said line occurring within a predetermined period of time.
21. In a signaling system, a plurality of transmission lines, a signaling path common thereto, a signaling device, means responsive to a change in the condition of one of said lines for operating said signaling device, an interrupter mechanism for intermittently operating said signaling device and means responsive only to more than one change in the condition of said lines occurring within a predetermined period of time for rendering operative said interrupter mechanism.

In witness whereof, I hereunto subscribe my name this 16th day of July, A. D. 1919.

WILLIAM L. DODGE.
